H. BRUNEAU

PICKER ROD

Filed May 20, 1924

Inventor:

Kingsley Bruneau
By Horatio E. Bellone

Attorney:-

UNITED STATES PATENT OFFICE.

HUDGER BRUNEAU, OF WOONSOCKET, RHODE ISLAND.

PICKER ROD.

Application filed May 20, 1924. Serial No. 714,560.

To all whom it may concern:

Be it known that I, HUGGER BRUNEAU, a citizen of the United States, residing at Woonsocket, in the county of Providence and State of Rhode Island, have invented 5 certain new and useful Improvements in Picker Rods, of which the following is a specification.

My invention relates to picker rods or 10 spindles for looms, and particularly to those of the detachable type.

Heretofore it has been customary to retain such rods by a set screw. The violent vibrations due to the movements of the lay and 15 the shuttles loosed the screw and released the rod with resultant smashing.

The essential objects of my invention are to overcome the accidental release of the rod; to facilitate lubrication of the same; 20 and to attain these ends in a simple, inexpensive, and adaptable structure.

To the above ends essentially my invention consists in such parts and in such combinations of parts as fall within the scope 25 of the appended claim.

In the accompanying drawings which form a part of this specification—

Figures 1 and 2 are a plan view and a 30 rear elevation respectively of the shuttle box upon which my device is mounted, and

Figure 3, a section on line 3—3 of Figure 1.

Like reference characters indicate like parts throughout the views.

In the embodiment of my invention herein illustrated 5 is a fragmentary showing of the portion of the lay adjacent the shuttle box 6 whose rear wall 7 constitutes the guide for the picker 9 actuated by the picker stick 40 10 to drive the shuttle 11.

Near the inner end of the rear wall 7 of the box is a lug 15 provided with a hole 16. Fixed to the outer end of the box is a tube 18 having a closed outer end 19 and disposed 45 in longitudinal alignment with the lug. In this instance the tube is fixed to the end wall 21 of the shuttle box by an attaching screw in a horizontal bracket or arm 22 integral with the tube 18. Near the open end 50 of the tube is slidably mounted a bearing member 24 provided with a central tapering bearing or cavity 26, and enclosing the inner

end of a helical spring 28 whose outer end abuts against the closed end 19 of the tube.

Fitted in the hole 16 of the lug 15 is bearing member 30 comprising a shank 31 and a squared head 32. The latter abuts against one face of the lug and has a conical cavity 34 extending to a central longitudinal bore 35. The shank 30 extends through and beyond the lug and is provided with an external thread 36. An oil cup 38 has a bowl 39 and a neck 40, the latter being provided with a central oil passage 41. At its end the passage is enlarged to form a cavity 42 in 60 which is a thread 43 engaging the thread 36 whereby the end face of the neck is tightened against the face of the lug 15 and the screw 31 is firmly held in the lug.

The picker rod 45 is tubular and provided 70 with conical ends 46 and 47 and contains a core or wick 48 of absorbent material extending throughout its length. A hole 50 in the wall of the rod near its outer end is for the emission of the lubricating oil extracted 75 and distributed upon the exterior of the rod by the reciprocation of the picker. The end 46 of the rod is seated in the cavity 26 of the cap or slide 24, while its opposite end 47 is seated in the cavity or bearing 34 of 80 the fixed member 31. The wick 48 is supplied with lubricant from the bowl 39 through the oil passage 41 and 35.

The rod may be manually removed, when necessary, by pushing it lengthwise against 85 the member 24 which yields sufficiently to permit the opposite end of the rod to be withdrawn and moved laterally of the member 31, whereupon the end 46 will be ejected by the action of the spring. When the rod 90 is in normal position the pressure exerted by spring 28 insures such a firm seating of its conical ends in their respective bearings as to insure retention of the rod despite any vibration of the loom.

The combination in the element 31 of the 95 functions of a seat for the rod, a retaining element for the oil cup, a conductor of the lubricant, and a binder to the supporting lug, affords a simple, strong, easily assembled, and simple construction.

I claim:—

In a loom, a shuttle box, a bearing member yieldingly supported by the box, a lug on the

box provided with a hole, a bearing member in alignment with the first bearing member comprising a shank in the hole provided with a central longitudinal passage and with a thread and a head engaging the lug provided with a cavity communicating with the passage, an oil cup comprising a bowl and a neck engaging the lug provided with a pas-

sage and with a thread engaging the first thread, and a tubular picker rod provided with a lateral oil opening and having one end engaging the first bearing member and having its opposite end seated in the cavity. 10

In testimony whereof I have affixed my signature.

HUDGER BRUNEAU.
